UNITED STATES PATENT OFFICE.

JOHN P. SWIFT, OF PAWTUCKET, RHODE ISLAND.

DESIGN FOR BRAID.

SPECIFICATION forming part of Design No. 36,609, dated October 27, 1903.

Application filed June 24, 1903. Serial No. 162,912. Term of patent 14 years.

To all whom it may concern:

Be it known that I, JOHN P. SWIFT, a citizen of the United States of America, and a resident of Pawtucket, Rhode Island, have invented a new, original, and ornamental Design for Braid, of which the following is a specification.

The figure of the drawing is a plan view of my newly-designed braid with the lines separated for clearness.

What I claim as new, and desire to secure by Letters Patent, is—

The ornamental design for a braid as shown. Signed at Pawtucket this 20th day of June, 1903.

JOHN P. SWIFT.
